**TOP DECK AND EXTENDABLE CLOSURE UNIT
FOR A STANDUP BUS-TYPE VEHICLE**

Patrick D. Patterson, 2099 Barrett St. 95124, and
Alwyne Z. Sanders, 63 N. 5th St., Apt. 6 95112,
both of San Jose, Calif.

Filed Feb. 5, 1969, Ser. No. 15,650

Term of patent 7 years

Int. Cl. D12—14

U.S. Cl. D14—27

FIG. 6.

FIG. 4.

FIG. 5.

FIG. 9.

FIG. 8.

FIG. 7.

FIG. 1 is a front perspective view of a top deck and extendable closure unit for a standup bus-type vehicle showing our new design;

FIG. 2 is a side view thereof;

FIG. 3 is a rear view thereof;

FIG. 4 is a top view thereof;

FIG. 5 is a side view thereof;

FIG. 6 is a front view thereof;

FIG. 7 is a perspective view thereof with the forward end extended;

FIG. 8 is a side view thereof;

FIG. 9 is a rear view thereof;

FIG. 10 is a top view thereof;

FIG. 11 is a side view thereof; and

FIG. 12 is a front view thereof.

The vehicle shown in broken lines is included for illustrative purposes only.

We claim:

The ornamental design for a top deck and extendable closure unit for a standup bus-type vehicle, as shown and described.
